ORCHARD HEATER

Howard J. Lambert, Los Angeles, Calif.

Application August 13, 1937, Serial No. 158,926

3 Claims. (Cl. 158—91)

My invention relates to improvements in orchard heaters of the type designed to be placed within an area to be heated, that is, in an orchard, or other outdoor area, in a shop or other 5 large structure which it is desired to heat.

The first object of my invention is to provide an improved orchard heater which will furnish a maximum amount of heat with practically no smoke or products of combustion discharged from 10 the stack thereof.

Another object of my invention is to provide a heater structure which can be applied to present fuel bowls or containers now used by many orchardists, thus greatly reducing the expense 15 thereof.

Another object of my invention is to provide a heater wherein the heat generated is so directed that the oil reservoir becomes heated to such an extent that not only the lighter gas vapors will 20 pass off, but the heavier gases will also be generated and released with the lighter gases, and directed into the combustion area of the apparatus.

Another object of my invention is to provide 25 improved means for admitting atmospheric air and for directing and mixing it most effectively with the gases generated in the heater, whereby to promote immediate combustion and to progressively increase such combustion until all the 30 gases and by-products are consumed.

Another object of my invention is to provide 35 in a heater of the character referred to, an air inlet pipe for directing outside air up into the combustion area to be mixed with any gases or products of combustion which may not have been fully consumed in reaching this upper combustion area.

Another object of my invention is to provide in 40 combination with an air inlet pipe of the character referred to a baffle member under which outside air is discharged from said air pipe.

Another object of my invention is to provide a 45 combustion chamber having therein a central upwardly convexed baffle member with means for directing outside air up into said combustion chamber and discharging it under said baffle member, with other means for supplying outside air through the wall of said chamber, substantially directly opposite said baffle member, thus 50 providing means for discharging outside air outwardly from the central part of said chamber, under said baffle member, and also for discharging outside air inwardly through said outer wall opposite said baffle member. This provides a 55 horizontal layer or area of fresh air so posi-

tioned that any unburned gases and products of combustion must pass through it and further combustion thereof result.

Other objects and advantages of my invention will appear from the following detailed description of one practical embodiment thereof, taken with the accompanying sheet of drawings, in which:

Figure 1 is a side elevation of an orchard heater embodying my invention, with parts broken away and other parts shown in section; and

Figure 2 is a fragmentary sectional view taken on line 2—2 of Fig. 1.

Referring now in detail to the embodiment of my invention here shown for explanatory purposes, 5 designates a fuel oil bowl or reservoir in common use, and having an inlet or supply opening in the top thereof with the usual cap cover 6. Said cap cover is provided with the usual damper arrangement for regulating the inflow 10 of air to the interior of the reservoir. Said fuel bowl has the usual neck portion 7, over which various kinds of combustion structures can be placed.

I have provided a pan-like member 8, having a 25 downwardly extending flange or collar portion 9, which fits over said neck portion 7, said pan-like member 8 having an outer circle of air inlet holes 10 therethrough, and an inner circle of smaller air inlet holes 11, as seen more clearly in 30 Fig. 2 of the drawing.

Seated within the flange 8' of said pan-like member 8, is a drum 12, provided at its upper end with a tapering extension 13, upon the upper end of which is placed a stack 14, substantially 35 in the manner illustrated.

I have also shown a hood or canopy 15 mounted over said extension 13, for deflecting heat downwardly around the fuel bowl, and for sheltering the combustion structure.

Directly over the central opening of the pan-like member 8, and over the neck portion 7 of the fuel bowl, I have placed a disc baffle member 16, provided on its under side with three supporting feet 17, 18, resting upon the bottom of 45 the pan-like member 8, which hold said baffle member 16 a short distance above the inflow from the fuel bowl to the drum 12, as indicated.

Mounted upon said baffle member 16 is an air tube 18, of angular form, the lower end of which 50 extends through said pan-like member 8, to receive outside air from under said member 8, and the upper end of which extends up into the combustion chamber formed within the drum 12, substantially in the proportions shown, and has 55

mounted upon its upper end an upwardly convexed baffle member 19, substantially as illustrated. Four outlet holes 20, are provided in the upper end of said tube, immediately under said 5 baffle, with a combined area equal to the area of said tube 18, for discharging air outwardly under said member 19, as indicated. Around said drum 12, opposite said baffle member 19, I have also provided a circle of air inlet holes 21, for 10 the inflow of air at this same level, thus providing a film or horizontal strata of fresh air within the combustion chamber and through which unburned gases or other products of combustion must pass in their upward movement, and which 15 causes renewed combustion thereof.

Thus fresh air passes upwardly through the holes 10 and 11 in the bottom of the member 8, to mingle with the gases coming up under the disc baffle 16, from the fuel bowl or reservoir, and 20 at the upper level, fresh air is discharged outwardly through the holes 20, under said baffle member 19, and inwardly through the holes 21 in the drum 12.

In operating my improved orchard heater, the 25 fuel oil is supplied to the fuel bowl 5 in the usual manner and is ignited. The amount of air admitted through the damper cap 6 governs the combustion in said fuel bowl. The air entering said cap 6 is preheated by the deflected and 30 radiated heat and the cover of said fuel bowl is also heated thereby. This promotes the development of gases within the fuel bowl and the combustion thereof.

As these ignited gases pass upwardly through 35 the neck 7 of said fuel bowl they are deflected by the baffle member 16, which is also heated, and as they are deflected outwardly under said member 16, they are intercepted by inflowing heated air through the holes 11 and 10, which greatly 40 promotes the combustion of said gases and the development of great heat. As said combustion continues and said burning gases rise in the combustion chamber within the drum 12, they come in contact with the upper baffle member 45 19, also heated, and with the heated fresh air being discharged outwardly through the holes 20, 20, immediately under said baffle member 19, and with the inflowing air through the holes 21, 21, which further promotes and perfects the 50 combustion taking place within said combustion chamber, with the result that practically no smoke at all is permitted to escape out through the stack 14.

The baffle member 16 becomes a cherry red 55 heat and this heat is reflected and radiated so as to preheat the gases therein and cause combustion thereof as they come into contact with the inflowing air through the air inlets 21, 21. The baffle member 19 is also heated in the same 60 manner and its heat is radiated upwardly and downwardly and further promotes the heating of the gases between said baffle members and within said combustion chamber, so that the inflowing, heated fresh air through the tube 18 65 and out the holes 20, and the air inflowing through the holes 21 in the wall of the combustion chamber, as nearly perfect combustion is secured within said combustion chamber as can be had.

This inflow of air and the combustion of the gases results in a powerful turbulence or series of combustions, setting up continuous vibrations or impulses which disturb the air currents.

While I have shown and described in detail a 5 practical embodiment of my invention, I am aware that changes in the details of construction and arrangement can be made without departing from the spirit thereof, and I do not limit myself to the showing made for explanatory purposes, except as I may be limited by the hereto appended claims.

I claim:

1. In an orchard heater, the combination with a fuel bowl in which fuel oil is ignited, said fuel 15 bowl having a neck-like opening therefrom, of a drum supported over said bowl and having an opening in its bottom to fit over said neck-like portion on said bowl, a baffle member in said drum immediately above said opening, whereby 20 ignited gases from said fuel bowl are directed outwardly and upwardly around the edge of said baffle member as they enter said drum, an air inlet tube having its lower end open to the outside of said drum through the bottom thereof 25 and extended inwardly over said baffle member and upwardly therefrom and having discharge openings in its upper end to discharge air outwardly radially therefrom to mix with the said ignited gases moving upwardly through said 30 drum, and a baffle member over the upper end of said tube to spread said gases.

2. In an orchard heater, the combination with a fuel bowl having a central outlet opening with flange therearound, of a drum having an opening in its bottom adapted to fit over said flange and to receive gases from said bowl therethrough, a baffle member in said drum over said opening and close thereto, an air tube having its lower end opening through the bottom of said drum 40 and extended upwardly and inwardly over said baffle member, a second baffle member on the upper end of said air tube, directly above said first baffle member, said tube having its upper end discharging air outwardly under said second 45 baffle member to mix with the ignited gases in said drum to cause the further combustion thereof.

3. An orchard heater including a fuel bowl to hold fuel oil, to be ignited therein, and having 50 a central outlet opening in its top, a drum having an opening in its bottom adapted to be connected over said outlet opening from said fuel bowl, the bottom of said drum having air inlet openings therethrough around and outside of its 55 connection with said fuel bowl, a baffle member in said drum over the opening to said fuel bowl to deflect gases therefrom outwardly around its edge, an air tube in said drum and having its lower end opening out through the bottom of said 60 drum and being extended inwardly and upwardly over said baffle member, a second baffle member at the upper end of said tube, said tube being open to discharge outside air under said second baffle member to mingle with the gases in said 65 drum, said drum having openings through its side opposite said second baffle member, and a stack over said drum.

HOWARD J. LAMBERT.
